(57) **CLAIM**

The ornamental design for a sleeve with bow tie, as shown and described.

DESCRIPTION

FIG. 1 is an elevated perspective view of the sleeve with bow tie, showing my design;

FIG. 2 is a front view of the sleeve with bow tie;

FIG. 3 is an opposing rear side view of the sleeve with bow tie;

FIG. 4 is a left side view of the sleeve with bow tie;

FIG. 5 is an opposing right side view of the sleeve with bow tie;

FIG. 6 is a top view of the sleeve with bow tie;

FIG. 7 is an opposing bottom view of the sleeve with bow tie; and,

FIG. 8 is another elevated perspective view of the sleeve with bow tie.

In FIG. 8, the features of the bottle shown in phantom lines are for illustrative purposes only and do not constitute a part of the claimed design.
